UNITED STATES PATENT OFFICE.

PAUL MAYDA, OF RANCHESTER, WYOMING.

RAIL CLAMP AND HOLDER.

1,238,171.

Specification of Letters Patent. Patented Aug. 28, 1917.

Application filed May 28, 1917. Serial No. 171,507.

To all whom it may concern:

Be it known that I, PAUL MAYDA, a citizen of the United States, residing at Ranchester, in the county of Sheridan and State 5 of Wyoming, have invented a new and useful Rail Clamp and Holder, of which the following is a specification.

The present invention appertains to rail clamps and holders, and is particularly an 10 improvement over the rail clamp and holder disclosed in my Patent No. 1,173,204, granted February 29, 1916.

It is the object of the invention to provide a device of the character indicated which is 15 improved generally in its construction and details, to enhance the utility and efficiency thereof, whereby the device will properly serve its office of preventing the excessive or dangerous sliding movement of the rail 20 upon the ties, especially when the rail is inclined or otherwise subjected to strains tending to displace the same longitudinally.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

The invention is illustrated in the accompanying drawings, wherein:—

35 Figure 1 is an end view of the device as applied to the rail.

Fig. 2 is a horizontal section taken on the line 2—2 of Fig. 1.

Fig. 3 is a longitudinal vertical section 40 taken on the line 3—3 of Fig. 1.

Fig. 4 is a bottom plan view.

In carrying out the invention, there is 45 provided a pair of companion or coöperating sections 1 and 2 to snugly underlie the rails R and of equal length. Said sections are readily cast or forged from suitable metal, and the section 1 is relatively wide while the section 2 is relatively narrow, the upper surfaces of said sections being flat 50 and flush when they are assembled. The remote or outer edges of the sections 1 and 2 are provided with the respective upper hooks 3 and 4 projecting toward one another and engageable over the edges of the base 55 of the rail.

The adjacent or inner edges of the sec-

tions 1 and 2 are provided with interengagable portions or means 5 arranged to lock together by a relative longitudinal movement of the sections, and whereby the sections will be drawn together to clamp the base of the rail, and to prevent the lateral separation of the sections. Thus, the lower surface of the section 1 is provided with a longitudinal groove 6 extending from end 60 to end adjacent the inner edge of said section, and forming a depending flange or tongue 7 along said edge. The section 2 is provided in its upper surface with a longitudinal groove 8 along its inner edge for 65 receiving the tongue 7, and said groove 8 forms an upstanding tongue or flange 9 engageable by a longitudinal movement in the groove 6. The grooves and tongues are arranged at a slight angle with respect to 70 the rail and the obliquity of the interengaging portions 5 serves to cause the sections to be drawn toward one another as they are interengaged by a relative longitudinal movement. The tongues and grooves are 75 of dovetailed cross section, due to the inclination of the contacting surfaces of the two tongues 7 and 9, as seen in Fig. 1, whereby to provide a more effective lock between the sections. 80

The widest section 1 is provided with a pair of depending oblique flanges or ribs 10 connected at one end by a web or abutment 11 which is adapted to abut against the side of one tie of the track, said abutment 90 being braced by the ribs 10. The sections 1 and 2 are reinforced by means of transverse ribs 13 and 12, respectively, with which said sections are formed. The ribs extend around the hooks from the tips thereof to 95 the adjacent portions of the two sections. The ribs 13 and 10 are in intersecting relation, as seen in Fig. 4, whereby the section 1 will be strong and not apt to break under the strains imposed thereon. The hook 4 100 is formed at the smaller end of the section 2 and integral with the respective ribs 12 with a driving portion 14 adapted to receive the blows of a sledge hammer or other driving implement, whereby when the section 1 is 105 in place against the rail base and tie, the section 2 can be driven forcibly into place.

A longitudinal bar 15 is fitted snugly within the hook 3, and the ends thereof are beveled to fit the beveled webs 16 with which 110 the section 1 and hook 3 are provided at the ends of said section. The bar 15 is thus dis-

posed between the webs 16 with its ends abutting thereagainst, and the outer edge of the bar 15 has ratchet teeth 17 interengaging with ratchet teeth 18 with which the 5 hook 3 is provided at the angle thereof. The inner edge of the bar 15 has ratchet teeth 19 for biting the respective edge of the rail base. The teeth 19 as well as the teeth 18 face in a direction to oppose the longitudinal 10 movement of the rail R in the direction of the arrow 33 in Fig. 2, while the teeth 17 face in the opposite direction to oppose and engage the teeth 18, whereby to resist the longitudinal movement of the bar 15 relative 15 to the section 1.

As a means for holding the bar 15 within the hook 3, bores 20 are drilled in the ends of the section 1, webs 16 and bar 15, and pins 21 are embedded in the bores 20 and are 20 provided with threaded heads 22 screwed within the ends of said bores to hold the pins in place.

The upper surface of the section 1 is provided above the space between the ribs 10 25 with a longitudinal channel 23, the end portions 24 of which are reduced both in width and depth, and a longitudinal bar or strip 25 is seated in said channel, and is composed of hard metal, the same as the bar 15. 30 The section 1 is formed with ratchet teeth 26 at the sides of the channel 23 facing in the same direction as the teeth 19, and the side edges of the strip 25 have oppositely facing ratchet teeth 27 interengaging with the 35 ratchet teeth 26, to resist the longitudinal movement of the strip 25 in the direction of the arrow 33. The end portions of the strip 25 are reduced, as at 28, to fit in the reduced ends 24 of the channel, thereby to assist in 40 holding the strip 25 snugly in place. The strip 25 has upstanding teeth or spurs 29 for engaging or biting into the lower surface of the rail base.

As a means for holding the strip 25 within 45 the channel 23, somewhat similar to the means for holding the bar 15 in place, whereby said strip and bar will be held assembled with the section 1 before and after the device is applied. Bores 30 are 50 drilled into the ends of the section 1 and strip 25, and pins 31 are fitted in said bores and are provided with threaded heads 32 screwed into the ends of the bores. The pins 31 and bores 30 are arranged at the side 55 edges of the strips 25, and there is a pin 31 as well as a pin 21 at each end of the section 1.

In applying the device, the section 1 is first clamped against the rail by a suitable 60 tool, with the abutment 11 bearing against

the tie, and the section 2 is then slid longitudinally into engagement with the section 1, and is driven into place, whereby the two sections 1 and 2 are interlocked and caused to tightly clamp or grip the base of the rail. 65 The present device will retain its firm grip upon the rail base, and will effectively resist the longitudinal displacement of the rail R in the direction of the arrow 33 in Fig. 2.

That rib 10 which bears against and slides 70 along the inner edge of the section 2 is provided with a slanting tongue 33 to slide longitudinally into a groove 34 with which said edge of the section 2 is provided.

Having thus described the invention, what 75 is claimed as new is:

1. A rail clamp and holder comprising two sections to fit below the rail base having hooks at their remote portions for engaging over the edges of the rail base and having 80 interengageable means at their adjacent portions to interlock by a relative longitudinal movement of the sections, one section having webs at its ends and the ends of the hook of 85 said section, said hook having ratchet teeth at its angle, a longitudinal bar fitting snugly within said hook and having ratchet teeth at its opposite edges, to engage the aforesaid ratchet teeth and one edge of the rail base, said webs, section and bar having a bore 90 drilled therein, and pins fitting in said bores to hold said bar in place.

2. A rail clamp and holder comprising two sections to fit below the rail base having hooks at their remote portions for engaging over the edges of the rail base, and having 95 interengageable means at their adjacent portions to interlock by a relative longitudinal movement of the sections, one section being relatively wide and the other relatively narrow, the relatively wide section having a longitudinal channel provided with reduced ends, the relatively wide section having ratchet teeth along the sides of the channel, a strip seated in said channel and having reduced ends fitting the reduced ends of the channel, the side edges of the strip having ratchet teeth engaging the aforesaid ratchet teeth, said strip having upstanding spurs to 100 engage the rail base, the relatively wide section and strip having bores drilled therein at the ends of said section, and pins fitting in said bores.

In testimony that I claim the foregoing as my own, I have hereto affixed my signature 115 in the presence of two witnesses.

PAUL MAYDA.
